(57) **CLAIM**

The ornamental design for a steering wheel for automobile, as shown and described.

DESCRIPTION

FIG. 1 is a rear perspective view of a steering wheel for automobile showing our new design;

FIG. 2 is a rear view thereof;

FIG. 3 is a top view thereof;

FIG. 4 is a right side view thereof;

FIG. 5 is a bottom view thereof;

FIG. 6 is a left side view thereof; and,

FIG. 7 is a front view thereof.

The broken lines depict portions of the steering wheel for automobile, that form no part of the claimed design.

1 Claim, 7 Drawing Sheets
